ABSTRACT OF THE DISCLOSURE

A tool for securing together by means of a seal the ends of a flexible band put around a package makes use of the movement of the sealing head away from the base of the tool necessary to disengage the sealing head from the closed seal to release tension in the part of the band between the seal and the band supply and then to sever the band. To avoid fibrillation, tension is released before severing by arranging the cutter to be moved by a part of a pawl after the pawl has been disengaged from a ratchet maintaining tension.

This invention relates to tool for banding packages, parcels or the like and is particularly, although not exclusively, for use with banding of the non-metallic type.

Banding tools are known which comprise a base portion providing a sealing station at which overlapping portions of a length of banding looped around a package can be joined together by a seal applied by means of a sealing device having jaws movable into and out of a sealing position at the jointing station, the tools including means for holding the free end of the band and means for tensioning after the band has been looped around the package, and a cutting device adapted to cut the upper of the overlapping bands and so free the banded package from the supply source. It is also known to use such tools with banding tape of the non-metallic type, and to release the tension in the banding prior to severing in order that splitting or fibrillation of the cut ends does not occur.

It is an object of the present invention to provide a banding tool of the kind set forth which includes several improved features and in particular a mechanism which provides more efficient operation of the sealing mechanism than prior devices.

It is a further object of the invention to provide a tool which makes better use of the essential operative movements during the banding and severing operation.

The present invention consists in a tool for banding packages, parcels or the like comprising in combination a base, a sealing station on the base and disposed intermediate the ends thereof, sealing means mounted on the base adjacent to the sealing station and hingeable away from the base, gripper means mounted on the base to one side of the sealing station to grip the free end of a band from a supply, tensioning means mounted on the base on the other side of the sealing station to tension the band after it has been passed around a package or the like such that there is an overlapping part adjacent to the sealing station, tension release means to release the tension in the strap after sealing, and severing means to sever the band from the supply, the tension release means and the severing means being actuated in succession by movement of the sealing means as it is hinged away from the base, after completion of the operation of the sealing means.

Normally the tool would be used with banding made from a plastic material such as nylon or polypropylene but banding of light gauge steel could be used. It is intended that the tool should be portable in as much that in use it could be put by hand into position on the pack-

2

age, however, a larger tool or machine which is stationary on its site of use is not beyond the scope of the invention.

The gripper means is preferably provided with a self locking device which enables the free end of the banding material to be trapped as the material is tensioned around the package and which is biased to the open position to enable the end of the band to be released automatically from the gripper when the tool is removed from the package.

10 The tensioning means to tension the banding material around the package may include a capstan carried by an axle journaled in the base and comprising at least one axially-directed open-ended slot which extends in the axial direction of the axle for approximately the width of the banding material.

15 The banding material having been passed around the package is inserted into one of the slots in which spring means are preferably provided to hold the banding material prior to being tensioned by rotation of the capstan.

20 It is also preferable that the means to tension the banding incorporates a pawl and ratchet device which is spring loaded so that when a predetermined tension of the banding material is reached the pawl will override the ratchet.

25 An embodiment of the invention will now be described by way of example with reference to the accompanying drawings in which:

FIG. 1 is a side view of a tool according to an embodiment of the invention,

30 FIG. 2 is an end view of the tool shown in FIG. 1.

FIG. 3 is a similar side view to that shown in FIG. 1 but with the sealing head raised,

FIG. 4 is a side view from the side opposite to that shown in FIG. 1 and in a different stage of operation,

35 FIG. 5 is a sectional elevation on the line 5—5 of FIG. 1.

FIG. 6 is a detailed view of the tensioning mechanism from one side,

FIG. 7 is a vertical cross section on the line 7—7 of FIG. 4,

40 FIG. 8 is a vertical longitudinal section through part of the device housing the sealing mechanism,

FIG. 9 shows the overlapping ends of the banding after sealing and severing,

45 FIG. 10 is a plan view of that part of the tool housing the gripper,

FIG. 11 shows a section on the line 11—11 of FIG. 10, and

50 FIG. 12 is a section on the line 12—12 of FIG. 10 and showing a banding tape pulled taut in the gripper.

The tool is of the type which incorporates mechanism to apply a seal to overlapping portions of the band and comprises the following major components which are best seen in FIGS. 3 and 6; a base 10 provided with a fixed handle 11, a band tensioning mechanism 12, a gripping device 14 and a sealing head 13 which is hingeable away from the base. These components will all be described in detail hereinafter as will their full operation, but in brief the arrangement of the components of the tool is such that the free end of the band can be inserted into the gripping device 14 where it is trapped as the band is pulled around the package. The supply end of the band is then inserted into tensioning mechanism 12 after tensioning the sealing head 13 is hinged to meet the base and a seal is applied to join the band. When the sealing head 13 is hinged away from the base it causes the actuation of mechanism which first releases the tension in the band and then severs it from the supply.

70 The gripping device 14 (FIGS. 10, 11 and 12) is positioned on the base 10 adjacent to the end remote from the handle and comprises a spindle 15 disposed trans-

versely of the base within a bore 16 straddling a slot 17 machined in the base member substantially midway between its sides. The slot 17 extends to a width consistent with the width of the band 19 (FIG. 12) and is undercut at its inner end so that it opens into a channel portion 20 in the base. The channel 20 is parallel to the spindle 15 and extends to one side of the base 10. The slot 17 is also tapered from the top face of the base 10 to the bottom end face as shown in FIG. 12.

That part of the spindle 15 which is within the slot 17 is cut away to provide a flat face 18 at a position approximating its diameter and the dimensions are such that in one position of rotation the flat 18 can be aligned with the channel portion 20. A spring 21 biases the spindle 15 towards the open position as shown in FIG. 11.

Conveniently, that part of the base 10 housing the gripping device 14 is made in two parts by machining away one corner of the base 10 to the required depth and providing a capping portion 22 (FIGS. 10 and 12).

Extending from the innermost part of the handle 11 are two spaced and parallel side members 23 which form the mounting for the band tensioning mechanism 12. The mechanism 12 includes a capstan 25 carried by an axle 24 journalled in the sidemembers 23. The capstan 25 is formed with four equally angularly spaced, open ended slots 26 extending parallel to the axis of the axle 24 and chordwise to the periphery of the capstan 25 (FIGS. 1 and 5). The capstan 25 is positioned on the axle 24 so that it is on the outside of one of the sidemembers 23 and is in line with the gripping device 14. The depth of the slots corresponds to the width of the band 19. Leaf springs 27 are secured to the end of the central part of the capstan 25 and have free portions which extend obliquely across the slots 26 and are urged towards the outer sides of the slots, the arrangement being such that when the band 19 is passed through any one of the four slots 26 it can be held by a spring 27 against the side of the slot and retained in the capstan 25 prior to the tensioning operation. The opposite end of the axle 24 extends outside the other of the two sidemembers 23 and carries the capstan drive mechanism comprising a ratchet wheel 29, a drive pawl 30, of a drive pawl and ratchet device 28 and a tubular tensioning lever 33. The drive pawl 30 is pivotally mounted between the forked end of the tensioning lever 33 adjacent to the ratchet wheel. The nose profile of the drive pawl 30 is such that two straight faces of the tooth meet substantially at right angles and engage with complementary profiles in the ratchet wheel 29. The nose 31 of the pawl 30 is held against the teeth of the ratchet wheel 29 during the tensioning by a plunger 78 and compression spring 32 which are housed with the tubular tensioning lever 33, a tension adjustment screw 34 being provided in the end of the tensioning lever 33. The loading of the spring 33 determines the maximum tension in the band 19.

A holding pawl and ratchet mechanism 37 is provided to prevent reverse rotation of the axle 24 during the tensioning operation and comprises a ratchet wheel 38, which is mounted on the axle between the side members 23, and a holding pawl 39, which is pivotally mounted between the sidemembers 23 above the ratchet wheel 38 and is operative to engage therewith (FIGS. 1 and 5). The profile of the engaging parts of the holding pawl and ratchet device 37 is essentially different from that of the drive pawl and ratchet device, the teeth on the ratchet wheel 38 being raked towards the reverse direction of rotation and the pawl 39 having a complementary hooked nose portion.

The tensioning lever 33 is normally urged towards a rest position by a torsion spring 36, as shown in FIG. 6, where the tail of pawl 30 engages a stop 35 and the nose 31 of the pawl is prevented from engaging the teeth of the ratchet wheel 29. The holding pawl 39 is also provided with a laterally extending toe portion 40 which abuts an adjacent cutting device 41 and a raised portion 46. The cutting device comprises a movable cutter 42 rotatably

held to the base structure adjacent to one end of the cutter 42 by a screw 43, disposed transversely of the direction of the band over the base and positioned above a fixed cutter 44 (FIGS. 1, 3 and 5). The movable cutter 42 is urged away from the fixed cutter 44 and into contact with the toe portion 40 by a spring 45. The raised portion 46 operates the cutting device 41 in a manner to be described.

Rotatably mounted on the axle 24 and adjacent to the outside faces of the sidemembers 23 are a pair of spaced parallel arms 47 which carry the sealing head 13. The sealing head 13 comprises two separate housings which accommodate and support the sealing means. The housings are bolted together during assembly of the parts. A first housing 48 which is nearest the handle 11 and to which the arms 47 are attached has bell shaped sidewalls and houses the sealing means the means comprising a toggle mechanism 49 generally indicated in FIGS. 7 and 8 and a rack and pinion mechanism 50 (FIGS. 1 and 8), operatively connected to the toggle mechanism 49 and to a hand lever 51. The arrangement is such that movement of the hand lever 51 in the direction of the arrow shown in FIG. 1 will cause the pinion 52 of the mechanism 50 to rotate in a clockwise direction and cause the rack 53 to move downwardly in a bore 54 within the housing 48. Movement of the hand lever 51 in the opposite direction raises the rack 53. Upward movement of the rack 53 is limited by the abutment of an external shoulder on the rack with an internal shoulder in the bore 54. The toggle mechanism 49 carries two pairs of movable jaws 55 which are disposed between T shaped guide members 56 (FIGS. 7 and 8). The members 56 are provided with a rectangular slot 57 which has a divergent mouth opening into the lower edge of the members 56, the edge protruding below the jaws 55. The jaw assembly is linked by pins 58 and the members 56 have limited vertical movement within the assembly. The housing 48 also provides a mounting for a spring biased plunger 59 (FIG. 1) which has a projection 60 at its lower end and it is this projection which contacts the raised portion 46 to actuate the cutter 42 and also release the second pawl 39 from the ratchet wheel 38 (FIGS. 1 and 5) as the sealing head 13 is hinged away from the base 10. The cutter spring 45 is considerably stronger than the spring biasing the plunger 59 and this feature together with the scope of the formations of the raised portion 46 and projection 60 which co-operate in each direction ensures that no actuation of the cutter takes place when the sealing head is moved towards the base 10. Adjacent to the first housing 48 and bolted thereto by means of four bolts 62 there is a second housing 61 which accommodates a stack of sealing clips 63. The clips 63 are spring urged towards the bottom of the housing 61 through which they can be ejected individually to a position within the slots 57 of the guide members 56. That part of the base 11 which is disposed between the cutting device 41 and the gripping device 14 constitutes the sealing station 65 and this part of the base is provided with two rectangular apertures 66 and 67. These apertures are coincident with the housings 48 and 61 respectively when the sealing head 13 is in the closed position. In this position the bottom parts of the housings 48 and 61 will seat in the recess 68 in the upper part of the base 10.

A pair of outwardly protruding lugs 69 on the end wall of the second housing 61 carry a spindle 71 horizontally and transversely disposed on the end wall at a point nearer the top than the bottom. On this spindle a cranked clip feed lever 70 is pivotally mounted. The upper arm of the lever 70 carries a roller 76 on its end part and is offset to one side of the housing 61 and aligned with a cam 72 attached to the sealing lever 51. The lower arm of the clip feed lever 70 is formed with a pair of spaced lugs 73 which carry a shackle pin 74 on which a sealing clip pusher 75 is mounted (FIGS. 2, 4 and 8). The pusher 75 is spring urged towards the base 10. The

arrangement of the levers 51 and 70 is such that movement of the lever 51 in the direction of the arrow shown in FIG. 1 causes the cam 72 to contact the roller 76 forcing the lever 70 to pivot away from the housing 61 as shown in FIG. 4.

In operation the tool is loaded in the position shown in FIG. 1 with a stack of seal clips 63 through an aperture in the top of the second housing 61. The tool is placed on the package to be banded. In the position of the hand lever 51 as shown in FIG. 1 the rack 53 is at the uppermost limit of its travel so that backward movement of the hand lever 51 in the direction opposite to the arrow in FIG. 1 causes the sealing head 13 to pivot rearwards about the axle 24 to the raised position shown in FIG. 3. In this condition the tool is ready for use. The free end of the band 19 is inserted into the slot 17 beneath the flat 18 so that the extremity enters the channel portion 20 and the bight portion is folded over the spindle 15 and onto the top of the base 10. The free end of the band 19 is trapped against an edge 77 within the slot 17 when the tape 19 is pulled establishing a frictional driving connection with the spindle 15 to turn the spindle 15 in an anti-clockwise direction against the action of the spring 21. The band 19 is then passed below the fixed cutter 44, around the package and back again above the fixed cutter in an overlapping relationship with the first end of the tape. It is then inserted into one of the four slots 26 of the capstan where it is held by the leaf spring 27 of that slot against the inner wall of the slot. The tape is now tensioned around the package by an oscillatory movement of the tensioning lever 33 which causes the capstan to turn forwards on each driving stroke and apply tension incrementally to the band 19. During the tensioning operation, on forward strokes of the lever 51 the operator must overcome the force of the torsion spring 36 and as the lever is pushed forwards the drive pawl 30 is released from the stop 35 and the nose 31 is held against the ratchet wheel 29 by the compression spring 32. Reverse rotation of the capstan is prevented by the engagement of the pawl and ratchet mechanism 37 and the pawl 30 overrides the teeth of the ratchet 29 on the return stroke of the lever 51. When the resistance of the capstan reaches the point where the nose 31 of the pawl 30 overrides the teeth of the ratchet on the driving stroke, the operator is aware that the required tension in the band 19 has been reached. The lever 33 is now allowed to return to the disengaged position by action of the torsion spring 36, as shown in FIG. 6. The tail of the pawl 30 resting against the stop 35 preventing the nose 31 from engaging the teeth of the ratchet wheel 29 so that the tensioning lever 33 is disconnected from the capstan. The tension in the banding tape 19 is now held by the pawl 39.

The sealing head 13 is then lowered onto the base 10 over the tensioned band 19 so that the overlapping part of the band enters the mouth of the slot 57 in the edge of the guide members 56. It is intended that the operator should move the sealing head 13 from the FIG. 3 to the FIG. 1 position by means of the hand lever 51 although it could be moved without the aid of the lever 51. However, since the force required to overcome the strength of the torsion spring in the clip feed mechanism when the cam 72 meets the roller 76 is much greater than the force needed to pivot the sealing head 13 on its axle 24, closure of the jaws 55 would not occur when the head 13 is hinged towards the base with the aid of the lever 51.

When the sealing head 13 is firmly on the base the sealing lever 51 is moved forwardly to the position shown in FIG. 4. In consequence the pinion 52 is rotated and the toggle mechanism 49 descends in its housing 48 to effect closure of the crimping jaws 55 over the overlapping portions of the band at the sealing station 65. Thus the band 19 is sealed as shown in FIG. 9. Forward movement of the sealing lever 51 also causes simultaneous movement of the clip feed lever 70 which is raised as

shown in FIG. 4. Backward movement of the lever 51 towards the position shown in FIG. 1 again raises the rack 53 to the upper limit of its travel and also allows the clip pusher 75 to feed a new clip 63 into position in the slots of the guide members 56. Further backward movement of the lever 51 pivots the sealing head 13 about the axle 24 and brings the projection 60 on the plunger 59 into contact with the raised portion 46 on the pawl 39 of the second pawl and ratchet device 37 and further backward movement causes the toe portion 40 of the pawl 30 to move downwardly and so release the nose of the pawl 39 from the ratchet wheel 38. As the drive pawl 30 of the first pawl and ratchet device 28 is also in its disengaged position the tension is released in that part of the banding tape 19 which is between the seal and the tensioning mechanism. The toe 40 of the pawl 39 also bears on the movable cutter 42. After the tension has been released the movable cutter 42 closes with the fixed cutter 44 and severs the upper portion of the overlapping band 19 which is between the seal and the tensioning mechanism 12.

After severing the band 19 from the supply the tool is removed from the tensioned and sealed strap by sliding it diagonally away from the sealed joint in the direction of the handle 11. Since the gripping device 14 is biased to the open position the end of the tape 19 will release itself automatically.

On a portable tool resting on a package downward movement of a lever from a vertical to a horizontal position, that is through about 90° is as much as can be provided if any appreciable force is to be exerted. It will be appreciated that the invention enables the whole of this movement to be used for crimping, by contrast with conventional tools in which the last part of the movement of the sealing lever is needed to operate the severing means. In a tool according to the invention a nearer mechanical advantage can therefore be provided for crimping the seals enabling them to be crimped more tightly or alternatively less force to be used by the operator.

The invention also enables simple movement of a single lever to be used both to close the head onto the base and crimp the seals and again open the sealing mechanism and raise the head from the base. Thus a natural "follow through" of these movements is possible.

We claim:

1. A tool for banding packages, parcels or the like comprising in combination a base, a sealing station on the base and disposed intermediate the ends thereof, sealing means mounted on the base adjacent to the sealing station and hingeably away from the base, gripper means mounted on the base to one side of the sealing station to grip the free end of a band from a supply, tensioning means mounted on the base on the other side of the sealing station to tension the band after it has been passed around a package or the like such that there is an overlapping part adjacent to the sealing station, tension release means to release the tension in the strap after sealing, and severing means to sever the band from the supply, the tension release means and the severing means being actuated in succession by movement of the sealing means as it is hinged away from the base, after completion of the operation of the sealing means.

2. A banding tool according to claim 1 in which the sealing means is provided with a hand lever movable with respect to the sealing means in one direction for closing a seal about said overlapping part of the band and in the opposite direction for releasing the seal from the sealing means, and the hand lever is also effective to move the sealing means towards and away from the base by movement of the hand lever in the same direction and respectively preceding and following the seal closing and releasing movements of the hand lever.

3. A banding tool as claimed in claim 1 in which the tensioning means includes a holding pawl engageable with

a ratchet so as normally to prevent movement of the ratchet in the direction for releasing tension and the tension release means comprises an abutment on the sealing means which engages the holding pawl on movement of the sealing means away from the base and serves to release the holding pawl from its engagement with the ratchet.

4. A banding tool as claimed in claim 3 in which the abutment is a spring biased detent which yields on engagement with the holding pawl during movement of the sealing towards the base but, on engagement with the holding pawl during movement of the sealing means away from the base, resists displacement in order to disengage the holding pawl from its associated ratchet.

5. A banding tool as claimed in claim 3 in which the severing means is actuated by the tension release means.

6. A banding tool as claimed in claim 3 in which the holding pawl is pivoted with respect to the base and includes a toe portion extending away from the pivot and a raised portion disposed between the toe portion and the pivot, the toe portion being so constructed and arranged as to actuate the severing means after disengagement of the holding pawl from the ratchet and the raised portion being the part of the holding pawl to be engaged by the abutment.

7. A banding tool as claimed in claim 6 in which the severing means includes a cutter pivotally mounted with respect to the base adjacent to one end of the cutter and disposed transversely of the direction of the band over the base in a position such that part of the cutter spaced from the pivot lies within the locus of the toe portion and in which the cutter is biased by spring means so as to be urged against the toe portion and consequently that end of the holding pawl which is remote from the toe portion is urged into contact with its associated ratchet.

8. A banding tool as claimed in claim 7 in which the abutment is a spring biased detent which yields on engagement with the holding pawl during movement of the sealing towards the base but, on engagement with the holding pawl during movement of the sealing means away from the base, resists displacement in order to disengage the holding pawl from its associated ratchet and in which the force due to the spring means urging the cutter into contact with the toe portion, the force due to the spring biasing the detent and the profile of the raised portion and that part of the detent which contacts the raised portion are so related that when the sealing means is moved towards the base no actuation of the severing means or tension release means occurs.

9. A banding tool as claimed in claim 1 in which the gripper means is biased to the open position and in use the free end of the band is inserted into the gripper in

that position and the act of applying tension to the band establishes a driving connection between the band and the gripper so that the gripper moves to a positive locking position, the band being released automatically from the gripper when the tool is removed from the package.

- 5 10. A banding tool as claimed in claim 1 in which the tensioning means includes a manually-operable tensioning lever coupled by a drive pawl and associated ratchet to a capstan in which the band is held during tensioning and which is uni-directionally rotated upon actuation of the tensioning lever and in which the capstan is carried at one end of an axle journaled in the base and comprises at least one longitudinally-directed, open-ended slot which serves together with spring means associated with the slot to hold the band prior to the tensioning operation.
- 10 11. A banding tool as claimed in claim 10 in which the spring means comprises a leaf spring secured to the capstan and having a free portion extending obliquely across the slot and urged towards one side thereof.
- 15 12. A banding tool according to claim 1 in which the tensioning means includes a manually-operable tensioning lever coupled by a drive pawl and associated ratchet to a capstan in which the band is held during tensioning and which is uni-directionally rotated upon actuation of the tensioning lever and in which the drive pawl is urged by spring force into engagement with or towards the ratchet, and wherein the nose profile of the pawl and the spring force together predetermine the tension of the band in operation of the tool.
- 20 13. A banding tool as claimed in claim 12 in which adjustment of the spring force is provided and hence the final tension in the band can be varied.
- 25 14. A banding tool as claimed in claim 1 in which the tensioning means includes a manually-operable tensioning lever coupled by a drive pawl and associated ratchet to a capstan in which the band is held during tensioning and which is uni-directionally rotated upon actuation of the tensioning lever and in which the tensioning lever is spring biased towards a rest position and means are provided for withdrawing the drive pawl from the ratchet when the tensioning lever is in the rest position.
